SOCK HANGER

Allen I. Field, 47 Valley Stream Road, Larchmont, N.Y.
10538, and Sidney P. Field, 226 Beach 134th St., Belle Harbor, N.Y.

Filed July 29, 1974, Ser. No. 492,512

Term of patent 14 years

Int. Cl. D6—08

U.S. Cl. D6—251

FIG. 5

FIG. 1

FIG. 4

FIG. 6

FIG. 2

FIG. 3

FIG. 1 is a front elevational view of a sock hanger showing my new design;

FIG. 2 is a top plan view thereof;

FIG. 3 is a bottom plan view thereof;

FIG. 4 is an end elevational view taken from the left of FIG. 1;

FIG. 5 is an end elevational view taken from the right of FIG. 1; and

FIG. 6 is a cross-sectional view taken on line 6—6 of FIG. 1.

We claim:

The ornamental design for a sock hanger, substantially as shown.
